UNITED STATES PATENT OFFICE.

LOUIS ROTH, OF NEW YORK, N. Y., ASSIGNOR TO STERLING BRONZE COMPANY, OF NEW YORK, N. Y., A CORPORATION OF NEW YORK.

DESIGN FOR A HANDLE.

Application filed March 25, 1922. Serial No. 1,386. Term of patent 7 years.

To all whom it may concern:

Be it known that I, LOUIS ROTH, a subject of Austria, residing at the city of New York, borough of Manhattan, county and State of New York, have invented a new, original, and ornamental Design for a Handle, of which the following is a specification, reference being had to the accompanying drawing, forming part hereof.

Figure 1 is a side elevation.
Figure 2 is a top plan view.
Figure 3 is an end view, and
Figure 4 is a cross section on the line 4—4 of Figure 1.

I claim:

The ornamental design for a handle, as shown.

LOUIS ROTH.
